GARMENT CONSTRUCTION

Jerome Giuseffi, Cincinnati, Ohio, assignor to
The Goodall Worsted Company, Sanford,
Maine, a corporation of Maine

Application June 24, 1938, Serial No. 215,660

1 Claim. (Cl. 2-268)

This invention relates to garment construction, and particularly to the provision of shoulder pads in coats of the unlined type commonly used for summer wear.

An object of the invention is to provide a coat of this kind with shoulder padding in order to effect the built-up shoulder construction usually seen only in coats of heavier materials in which linings are ordinarily provided.

Another object is to provide a novel method for applying the shoulder pads to lighter type garments of the kind indicated.

Another object is to provide a novel form of shoulder pad for garments of the type mentioned.

Another object is to effect such construction in a simple and effective manner and at a minimum of cost.

These and other objects are attained by the means and methods described herein and illustrated in the accompanying drawing, in which:

Fig. 1 is a side elevational view of a coat comprising the means of the present invention, the neck portion of the coat being omitted.

Fig. 2 is a view similar to Fig. 1 showing the coat turned with the inner side out to disclose the means of this invention in operative position.

Fig. 3 is a fragmental view showing the inside portions of a coat, particularly the shoulder and sleeve head portions thereof with the shoulder pad of this invention attached to the sleeve head portions but detached from the shoulder portions of the coat.

Fig. 4 is a bottom plan view of the shoulder pad of the present invention with a portion thereof broken away.

Fig. 5 is a cross-section through the shoulder and adjacent sleeve portions of a garment constructed according to this invention.

As already suggested, it has been possible heretofore to achieve an effective padded shoulder construction only in coats of the heavier variety in which lining is provided, the padding being disposed beneath the lining. In garments of the lighter kind, there being no such lining provided, the padding has been omitted, with a consequent loss in regard to a trim and squared-off appearance of the shoulders.

The present invention makes it possible to apply shoulder pads in garments provided only with interior shoulder facing and yoke, the pads being superimposed upon and attached to the shoulder facing and yoke and to the sleeve head portions of the garment.

In greater detail and with reference to the drawings, the pad of this invention is shown in

Fig. 4 and may comprise a body 8 of suitable padding material, interior padding covers 9 and 10, a top cover 11 of finish material, and a partial bottom cover 12, likewise of finish material. The padding 8 and interior covers 9 and 10 may be 5 suitably secured together by stitching 13 and the parts of the pad as a whole attached together by edge stitching 14. This pad is of the type having an open or unstitched edge, shown at the bottom of Fig. 4. At this portion of the pad, the 10 finish cover 11 is formed to extend as at 15 beyond the remainder of the pad for a purpose to be described.

The coat illustrated in Figs. 1, 2 and 3 is of the type comprising a body 16 having sleeves 17 18 and provided on the inside with facing 18 extending forwardly from the stitching lines 19 and 20 (Fig. 2) to the front vertical edges of the coat. A yoke 21 is provided in the coat, extending, as seen in Fig. 3, down to the armhole of the coat. 20 It may be noted that in Fig. 2 the right side of the coat is shown, whereas the left side portions are shown in Fig. 3.

The pad of the present invention is applied to the coat by sewing the edge of the extension 15 25 of the pad to the upper portion of the inside of the sleeve head by the same stitching utilized for attaching the sleeve to the armhole portions of the coat. For this operation, the pad would ordinarily be held in a reversed position, as seen 30 in Fig. 3, while said edge thereof is attached as described. The attached edge of the extension 15 is indicated at 22. The edge of the body portion 16 of the coat is indicated at 23 and the edge of the facing inside the coat is indicated at 24. 35 Simultaneously with this operation, the end edge of the yoke 21 is attached, as at 25, to the armhole portion of the coat.

It will be seen that piping 26 is applied around the joined edges at the armhole of the coat, 40 the ends of the piping extending, as suggested at 27, inwardly of the ends of the attached edge of the extension 15 of the pad.

After this initial attachment of the pad, the latter is turned over and superimposed, as indicated by the broken line 30, upon the shoulder portions of the coat, that is, upon the facing 18 and yoke 21 and is thereafter attached to these parts by suitable stitching 28 around the edge of the pad. It will be noted that this turning 45 over and attachment to the pad results in the extension 15 enclosing the open edge portion of the pad so that a neat and finished appearance is achieved.

In Fig. 2 it will be seen at the upper right hand 55

portions of the armhole that the pad, in operative position, extends beyond the yoke 21, as indicated at 29. The under-portions of the pad are therefore readily visible inside the coat, but the partial bottom cover 12 of the pad which, like the top cover 11, may be of the same finish material as the yoke 21, prevents the interior portions of the pad from being seen.

The pad itself and the manner of applying it are simple and effective and add little to the construction cost of the coat, at the same time achieving the trim and built-up appearance desirable in garments today.

What is claimed is:

The method of positioning a shoulder pad in a garment provided with a shoulder and a sleeve stitched thereto, the method consisting of sewing an edge of the pad to the edge of the shoulder inside the garment and with the same stitching attaching together said sleeve and shoulder, and subsequently placing and securing the pad in superimposed position on the inner face of the shoulder.

JEROME GIUSEFFI. 10
